NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

TOP-LATCH MECHANISM FOR PANIC-BOLTS.

1,203,116.

Specification of Letters Patent. Patented Oct. 31, 1916.

Application filed April 8, 1916. Serial No. 89,969.

To all whom it may concern:

Be it known that I, NORMAN B. HURD, a citizen of the United States of America, residing at New Britain, Connecticut, have invented a new and useful Top-Latch Mechanism for Panic-Bolts, of which the following is a specification.

My invention relates to door locking mechanism of the type comprising door locking means and controlling means associated therewith including a cross-bar or the like so positioned on the door as to be engaged with certainty in the event of a panic or the like, requiring a quick release and opening of the door.

One of the main objects of my invention is to insure certain, positive and quick release of the door locking mechanism.

Other objects are to reduce the cost of devices of this character and to do this without in any way sacrificing the strength or efficiency of the device.

Other objects and features of the invention will appear as the specification proceeds.

The present invention is closely related to and constitutes in the main an improvement of the bolt set forth and broadly claimed in my U. S. Letters Patent No. 1,145,590 of 30 July 6, 1915.

In the accompanying drawings wherein I have illustrated the invention embodied in a practical form: Figure 1 is a vertical sectional view showing the invention applied to 35 a door and door casing and with the parts in the door-unlocked position. Fig. 2 is a similar view with the parts in the door-locked position, the latch housing being shown in section. Fig. 2^a is a more or less 40 fragmentary view looking into the rear side of the center casing in which the handle is mounted. Fig. 3 is an enlarged rear view looking into the latch housing the cap or cover plate having been removed. Fig. 4 is 45 a detail perspective view of the abutment head carried by the upper end of the vertically movable bar. Fig. 5 is a similar view of the pivoted latch bolt.

Taking up the drawings now more in detail, 1 represents a door, 2 the overhead part of the door casing and 3 the lower part or floor which broadly considered constitutes a part of the casing.

4 is a vertically movable bar suitably

mounted on the door, it being guided and 55 supported in the present instance at its lower end by a guide bracket 5 and at its upper end in a latch housing 6.

The door lock in the present disclosure includes both upper and lower bolts which 60 engage suitable keepers on the upper and lower parts of the door casing. The lower keeper in the specific form shown comprises a socket 7 and the lower bolt in this instance is in the form of a bar 8 guided in the 65 bracket 5 and operatively connected with the lower end of the upper bolt bar 4, as by means of a walking beam 9 engaging at its opposite ends with pins 10 on the adjacent ends of the upper and lower bars. 70

The mechanism for releasing the lock comprises in the present disclosure a crossbar 11 designed to extend across the face of the door and pivotally supported at its ends at 12 in the center bracket 5. The bolt operating bar 4 differs from such bars in common use in that instead of being a gravity bolt it is normally sustained in upraised position. The means for normally sustaining this bar consists in the instance illustrated of a 80 spring 15 coiled about the upper end of the bar and seated in the lower end portion of the latch housing 6. The operating connections from the handle or crossbar 11 comprises in the illustration an arm 16 carried 85 by the crossbar and engaging beneath a lug 17 on the upper end of the lower bar 8.

It will be obvious from the description thus far that the vertically movable bar is normally sustained in the upraised position, 90 in which position the lower locking bolt is engaged with its keeper and it will further be clear that when the handle or crossbar is pressed against, as indicated at Fig. 1 the connections described will be operated to lift 95 the lower bolt and release it from its keeper and through the medium of the walking beam, to depress the upper bar 4.

Taking up now the construction of the other, and in this case, upper, locking bolt, 100 the same is illustrated as in the form of a pivoted latch bolt of substantially U-shaped formation providing an upstanding projecting latch nose 20 and an upstanding lug or trigger 21, said latch bolt being mounted on 105 a pivot pin 22 supported between the side walls of the latch housing. This pivoted bolt is further provided with a dependent

lug 23 providing a side face 24 for engagement with the side of an abutment head and a lower face 25 for engagement with the top of such abutment head.

5 The abutment head above referred to is indicated at 26 and is carried by the upper end of the bar 4, it being, in the illustration, formed as a separate block secured on the upper end of the bar by means of a pin 27. 10 This abutment head or block is provided with a side abutment face 28 for engagement with the side abutment face 24 of the latch and a top abutment face 29 for engagement with the lower abutment face 25 15 of the latch bolt.

In the normal, or door-locked position as indicated in Fig. 2, the operating bar is in the upraised position, and the side abutment face 28 of the abutment head lies in back of the abutment face 24 of the dependent lug on the latch bolt and so locks the latch bolt against retraction. When however the operating bolt bar 4 is depressed, this locking face of the abutment head is 20 carried away from locking face 24 of the latch bolt thereby freeing the latch bolt and permitting it to swing downward in the position indicated in Fig. 1 wherein the lower abutment face 25 of the latch bolt overlies 25 and engages over the top of the abutment head, thereby locking the bolt operating bar in its depressed and door-unlocked position. The pivoted latch bolt is preferably so balanced that it will when released by the withdrawal of the abutment head swing downward 30 by gravity as illustrated. To limit this downward swinging movement the latch bolt is usually provided with a stop lug 30 which, as indicated in Fig. 1, is arranged 35 to engage with the side of the abutment head.

The keeper for the upper bolt may be of a suitable construction and in the present instance I employ for this a lug or stop 31 45 dependent from the top of the door casing and providing on the inner side thereof an abutment face 32 for engagement by latching nose 20 and at the outside thereof an abutment 33 for engagement by the trigger 50 21 of the latch bolt.

From the foregoing it will be apparent that as soon as the locking bolts have been fully released the operating bar will become automatically locked and the lower bolt will 55 be thereby held in retracted position, the upper bolt having at this time fallen by gravity into its retracted or released position. This is the condition illustrated in Fig. 1. Fig. 1 also illustrates how as the 60 door is pushed closed the trigger on the latch bolt engages the abutment face 33 on the door casing and so swings the latch bolt up into projected position, at the same time freeing the operating bar from restraint and 65 permitting the spring or other sustaining

means to exert itself and lift the operating bar into the upper position wherein it locks the latch bolt in the projected position to which it has just been restored.

What I claim is:

1. In a door lock of the character set forth, the combination with a door and door casing, of a vertically movable bar mounted on said door, a pivoted bolt mounted on the door, a keeper on the door casing for said pivoted bolt, an abutment head on the vertically movable bar arranged in the raised position of the vertically movable bar to engage and lock the pivoted bolt in projected position, means for normally sustaining the vertically movable bar in raised position and means for lowering the vertically movable bar to thereby free the abutment head thereon from locking engagement with the pivoted bolt. 70 75 80 85

2. In a door lock of the character set forth, the combination with a door and door casing, of a vertically movable bar mounted on said door, a pivoted bolt mounted on the door, a keeper on the door casing for said pivoted bolt, an abutment head on the vertically movable bar arranged in the raised position of the vertically movable bar to engage and lock the pivoted bolt in projected position, means for normally sustaining the vertically movable bar in raised position and means for lowering the vertically movable bar to thereby free the abutment head thereon from locking engagement with the pivoted bolt, a tail piece on the pivoted bolt engaging the vertically movable bar in the depressed position thereof to lock said bolt in such depressed position and a trigger on the pivoted bolt arranged to engage a stationary abutment on the door casing in the closing movement of the door to restore the pivoted bolt to projected position and to release the vertically movable bar from restraint of the pivoted bolt. 90 95 100 105 110

3. In a door lock of the character set forth, the combination with a door and door casing, of a vertically movable bar mounted on said door, a pivoted bolt mounted on the door, a keeper on the door casing for said pivoted bolt, an abutment head on the vertically movable bar arranged in the raised position of the vertically movable bar to engage and lock the pivoted bolt in projected position, means for normally sustaining the vertically movable bar in raised position, means for lowering the vertically movable bar to thereby free the abutment head thereon from locking engagement with the pivoted bolt and a locking bolt operated by the vertically movable bar. 115 120 125 130

4. In a door lock of the character set forth, the combination with a door and door casing, of a vertically movable bar mounted on the door, means for yieldingly sustain-

- ing said bar in elevated position, a pivoted latch bolt on the door, a keeper for said latch bolt on the door casing, an abutment head on the upper end of the vertically movable bar arranged to engage the latch bolt in the raised position of said bar and thereby lock said latch bolt projected, means on the latch bolt engaging the vertically movable bar when said bar is depressed to lock said bar in depressed position, means for depressing the vertically movable bar and a trigger on the latch bolt arranged for engagement with an abutment on the door casing in the closing movement of the door to restore the latch bolt to projected position and free the vertically movable bar from the restraint of the latch bolt.
5. In a door lock of the character set forth, the combination with a door and door casing, of a vertically movable bar mounted on the door, means for yieldingly sustaining said bar in elevated position, a pivoted latch bolt on the door, a keeper for said latch bolt on the door casing, an abutment head on the upper end of the vertically movable bar arranged to engage the latch bolt in the raised position of said bar to thereby lock said latch bolt projected, means on the latch bolt engaging the vertically movable bar when said bar is depressed to lock said bar in depressed position, means for depressing the vertically movable bar, a trigger on

- the latch bolt arranged for engagement with an abutment on the door casing in the closing movement of the door to restore the latch bolt to projected position and free the vertically movable bar from the restraint of the latch bolt.
6. In a door lock of the character set forth, the combination with a door and door casing, of a latch bolt pivoted on the door having an upstanding latching nose, an upstanding trigger spaced therefrom and a dependent projection having abutment faces for engagement with the side and top surfaces of an abutment head, a vertically movable bar on the door and an abutment head on the upper end of said bar, means for normally yieldingly sustaining said bar with the side face of the abutment head thereon in locking engagement with the side abutment face on the dependent lug of the latch bolt, means for depressing said bar whereby to permit said latch bolt to swing down into position with the second abutment face thereon engaging over the top of the abutment head, a keeper on the door casing for the latch bolt and an abutment surface on the door casing arranged in the door closing movement to be engaged by the upstanding trigger of the latch bolt.
